ARTHUR A. McCANN AND CHARLES STOTZ, OF ST. LOUIS, MISSOURI, ASSIGNORS TO
DIAMOND WOOD HEEL & MFG. COMPANY, OF ST. LOUIS, MISSOURI, A CORPORATION
OF MISSOURI.

WOOD-HEEL-TURNING MACHINE.

Application filed November 9, 1923. Serial No. 673,674.

This invention relates to machines for shaping wooden heels.

In the process of shaping wooden heels, the heel blank, which usually has the breast portion already formed, is clamped in a support or jack and presented to a rotating cutter. The jack is moved with respect to the cutter and is guided during such movement in such a way as to give the heel the proper contour. In certain types of machines each side of the heel is presented to the cutter separately in successive operations. It is important in forming wooden heels and particularly in the case of heels for women's shoes, where the top is comparatively small, that both sides be formed alike so that the finished heel will be truly symmetrical.

In the types of machines at present in use, the guides which determine the movement of the jack in shaping the heel must be carefully formed so as to insure the same movement for shaping both sides in order that the heel may be symmetrical. This requires that before the machine can be put into productive operation the guides will require a considerable amount of filing or grinding so as to shape them in the desired manner.

One of the objects of this invention is to provide a heel forming machine which may be adjusted independently for forming the two sides of the heel so as to insure cutting the heel symmetrically on both sides.

Another object of this invention is to provide such a machine in which the guides controlling the jack may be adjusted both with respect to the total movement of the jack and also separately with respect to each half movement so as to form symmetrical heels.

Further objects will appear from the detail description taken in connection with the accompanying drawings, in which:

Figure 1 is a plan view of a heel forming machine embodying this invention;

Figure 2 is a front elevation of the same;

Figure 3 is a section on line 3—3, Figure 1; and

Figures 4 and 5 are outlines showing symmetrical and unsymmetrical heels.

Referring to the accompanying drawings, 50 1 designates a frame upon which the machine is mounted and which may carry a table or trays or the like for holding a supply of unfinished and finished heels, the operator drawing on the supply of unfinished heels 55 and returning finished heels to their proper

tray. This frame may also carry the driving motors for the cutters. These motors are not shown on the drawings.

Mounted on the frame 1 is a plate 2 which carries the moving parts of the machine. 60 This plate has mounted thereon bearings 3 and 4 in which the spindles 5 of the two cutters 6 are journaled. The spindles 5 are each provided with a pulley 7 adapted to accommodate a belt 8 suitably driven from a suitable motor, not shown. The cutters 6 are thus driven at a high speed and rotate on a vertical axis. The frame 2 also carries bearings 9 and 10 which support a vertical spindle 11 upon which a swinging arm 12 is arranged to pivot. The arm 12 has mounted therein at the extremity thereof a vertical rod 13 which is adapted to slide and rotate in the arm 12. This rod carries at its upper extremity a support or jack 14 provided with a suitable clamp 15 for holding the heel blank 16. The rod 13 is provided at its lower end with an arm 17 rigidly connected thereto which carries a horizontal roller 18 for a purpose which will be hereinafter described. 80 The support 14 is really pivoted at 19 on a head 20 rigidly fixed to the upper end of the rod 13. The support 14 also carries a roller 21 similar to the roller 18.

Mounted on the frame 2 near its lower end 85 is a pair of side brackets 22 extending forwardly from the plate 2 and inwardly toward each other. The ends of these brackets are connected by a cross-bracket 23 on which are pivoted at 24 a pair of guides 25. The guides 25 extend straight across the front of the machine opposite the cutters 6 and have curved ends 26 beyond the cutters. The guides are symmetrical with respect to their division point 270 opposite the middle of the machine. The outer ends 26 of these guides are supported by adjustable links 27 connected at 28 to the brackets 22. The guides 25 are supported by the pivot 24 and the links 27 and may be adjusted, by adjusting said links, to any desired degree of inclination from front to rear. These guides 25 are adapted to support and guide in its movement the roller 18 on the lower end of the rod 13.

Adjustably mounted on the plate 2 and above the brackets 22 is a similar pair of brackets 29 connected by a cross-bracket 30 on which are pivoted at 31 a pair of upper guides 32. These upper guides are similar 110

to the guides 25 and are adjustably supported at their ends by links 33 adjustably connected to the brackets 29. These guides 32 are also divided at their middle point 34 so as to be separately and independently adjusted. The upper guides 32 are adapted to support and guide in its movement the roller 21 on the heel blank support 14. The brackets 29 have a slotted connection 35 with the plate 10 2 so that they may be adjusted for elevation.

The roller 18 resting on the guides 25 supports the rod 13 at an elevation determined by the position of the roller 18 on the guides. This determines the elevation of the heel 15 blank 16 with respect to the cutters 6. The roller 21 resting on the guides 32 determines the inclination of the heel blank with respect to the cutters.

In the operation of this machine, the operator places the blank 16 in the support 14 and against a suitable stop 36 and then clamps it in place by means of the clamp 15. He then swings the handle 37 of the support 14 to one side, at the same time swinging the arm 12 to the same side until the roller 21 comes against a stop-screw 38 accurately placed on the guide 32. At the same time the arm 12 is moved toward the cutters 6 on that side until the guide-plate 39 on the head 20 30 comes against a stop 40 mounted in front of the bearing 4. Each bearing 4 is provided with such a stop 40 and the guide-plate 39 which contacts therewith is formed so as to give the heel base its proper outline when the holder 14 is rotated so as to carry the heel blank past the cutter. When the operator has moved the blank holder as described so that the guide plate 39 contacts with the stop 40, the heel blank will be brought against the cutter 6 so as to cause the cutter to form the side of the heel adjacent the breast. The handle 37 is then swung forwardly, keeping the guide-plate 39 in contact with the stop 40, until the handle 37 stands substantially perpendicular to the plate 2. During this movement the blank will be guided by the guide-plate 39 and the guides 25 and 32, all in combination, so as to form one side of the heel up to the middle of the back thereof. The operator then moves the blank out of engagement with that cutter and swings the holder to the opposite side of the machine so as to engage the other cutter in a manner similar to that described for the first cutter. By a similar movement of the handle 37 from the extreme side position to its forward position perpendicular to the plate 2, the other side of the heel is now formed. By these two operations the forming of the heel is completed. 50 60 65

As pointed out previously it is important to have the finished heel symmetrical. By independently adjusting the inclination of each of the guides 25 and each of the guides 32 and providing in combination therewith cutters 6 of a suitable form, a heel of substantially any

desired contour can be formed. Since, however, the formation is carried out in two steps, it is liable to occur that the movements of the heel blank in forming the two sides are not exactly alike and if this is the case the finished heel will not be symmetrical. In accordance with this invention the movements of the blank in forming the two halves may be adjusted independently of each other so that the two halves may be formed exactly alike. 75

It will be evident that in accordance with this invention provision is made not only for varying the shape of the heel by adjusting the upper and lower guides but also for insuring the formation of a symmetrical heel by adjustably guiding the blank support so as to regulate independently the cuts taken from the two halves of the blank. The path of the blank support is thus adjusted so as to balance the cuts on the two halves and make the heel symmetrical. Since each guide does its share in determining the shape of the heel on that side and the guides may be adjusted so as to control the cuts on each side independently, symmetrically formed sides for the heel are insured and at the same time, since the two guides of each pair merge at the middle, an accurate joining of the two formed surfaces at the middle of the back of the heel is insured. 85 90 95

The pivots 24 and 31 are removed forwardly from the cutters while the adjustable links 27 and 33 are arranged to adjust the elevation of the rearward ends of the guides. A compound adjustment is thus provided by means of which practically any shaped heel may be formed and formed symmetrically. 100

In the machines at present in use in which the upper and lower guides are not separated into two independently adjustable halves, it often happens that an unsymmetrical heel is formed having a shape somewhat as indicated in Figure 5. In such a case it requires a great deal of filing and manipulation of the guides to correct the difficulty. In accordance with this invention on the other hand, adjustment of one side or the other of one of the guides may be made independently of all other adjustments until a symmetrical heel is obtained as indicated in Figure 4. 105 110 115 What has often proved in the past to be an almost insurmountable difficulty in the use of this type of machine is thus eliminated by this invention.

It is obvious that various changes may be made in details of construction without departing from the spirit of this invention; it is, therefore, to be understood that this invention is not to be limited to the specific details shown and described. 120

Having thus described the invention, what is claimed is:

1. In a machine of the character described, the combination with cutting means, of a heel support, means for mounting said support 130

- for movement with respect to said cutting means, guides for said support adapted to respectively determine the shape of the two halves of the heel, and means for independently adjusting said guides. 5 the movement of said support, and means for independently adjusting said sections. 50
2. In a machine of the character described, the combination with cutting means, of a heel support, means for mounting said support for movement with respect to said cutting means, guides for said support adapted to respectively determine the shape of the two halves of the heel, and means for adjusting said guides adapted to regulate the cuts taken from the two halves of the heel. 10 8. In a machine of the character described, the combination with cutting means, of a heel support, means for mounting said support for movement with respect to said cutting means, a guide composed of sections merging into one another and adapted to control the movement of said support, and means for independently adjusting said sections. 55
- 15 3. In a machine of the character described, the combination with cutting means, of a heel support, means for mounting said support for movement with respect to said cutting means, and guides adapted to tip said support in order to regulate independently the cuts taken from the two halves of the heel. 9. In a machine of the character described, the combination with cutting means, of a heel support, means for mounting said support for movement with respect to said cutting means, guides for effecting compound adjustment of said support, and means for adjusting said guides in order to regulate the 60 cuts taken from the two halves of the heel. 65
- 20 4. In a machine of the character described, the combination with cutting means, of a heel support, means for mounting said support for movement with respect to said cutting means, guides adapted to tip said support during its movement, and means for independently adjusting said guides. 10. In a machine of the character described, the combination with cutting means, of a heel support, means for mounting said support for movement with respect to said cutting means, guides for elevating said support, guides for tipping said support, and means for adjusting said guides in order to regulate the cuts taken from the two halves 70 of the heel. 75
- 25 5. In a machine of the character described, the combination with cutting means, of a heel support, means for mounting said support for movement with respect to said cutting means, and a guide for said support pivoted on an axis adjacent its forward edge, and means for adjusting said guide. 11. In a machine of the character described, the combination with cutting means, of a heel support, means for mounting said support for movement with respect to said cutting means, guides, each composed of sections, for effecting compound adjustment of said support, and means for adjusting said sections. 80
- 30 6. In a machine of the character described, the combination with cutting means, of a heel support, means for mounting said support for movement with respect to said cutting means, guides for said support pivoted on an axis removed from said cutting means, and means for independently adjusting said guides. 12. In a machine of the character described, the combination with cutting means, of a heel support, means for mounting said support for movement with respect to said cutting means, a sectional guide for elevating said support, a sectional guide for tipping said support, and means for adjusting 85 said sections. 90
- 35 7. In a machine of the character described, the combination with cutting means, of a heel support, means for mounting said support for movement with respect to said cutting means, sectional guides adapted to control
- In testimony whereof we affix our signatures this 5th day of September, 1923.
